CLAIM

The ornamental design for a decanter, as shown and described.

DESCRIPTION

FIG. 1 is a top, front and right side perspective view of a decanter showing my new design;

FIG. 2 is a bottom, rear and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is an exploded isometric view of FIG. 1.

The broken lines showing the decanter illustrate environmental subject matter and form no part of the claimed design. The remaining broken lines show features of the decanter that form no part of the claimed design.

1 Claim, 9 Drawing Sheets
